[57] CLAIM

The ornamental design for a truck for a rail traversing car, as shown and described.

DESCRIPTION

FIG. 1 is a perspective view of a truck for a rail traversing car showing the top, front and one side of the ornamental design.

FIG. 2 is a perspective view thereof showing the top, rear and opposite side to that shown in FIG. 1 on a reduced scale, it being understood that the broken lines are for illustrative purposes only.

The bottom of the truck is understood to be flat and unornamented.

FIG. 2
